DESIGN FOR A HAT

Doris Vernon, New York, N. Y.

Application February 16, 1943, Serial No. 109,555

Term of patent 3½ years

To all whom it may concern:

Be it known that I, Doris Vernon, a citizen of France, residing in New York city, county of New York, and State of New York, have invented a new, original, and ornamental Design for a Hat, of which the following is a specification, reference being had to the accompanying drawing, forming part thereof.

Fig. 1 is a front perspective view of a hat showing my new design with the brim turned up.

Fig. 2 is a rear perspective view of the hat shown in Fig. 1 with the brim lowered and the hat tilted downwardly.

Fig. 3 is a top plan view of the hat.

I claim:

The ornamental design for a hat substantially as shown.

DORIS VERNON.
